UNITED STATES PATENT OFFICE.

GEORGE B. OWEN, OF WINSTED, CONNECTICUT, ASSIGNOR TO WM. L. GILBERT CLOCK COMPANY, OF WINSTED, CONNECTICUT, A CORPORATION OF CONNECTICUT.

GEAR-WHEEL.

1,080,160.

Specification of Letters Patent.

Patented Dec. 2, 1913.

Application filed December 14, 1912. Serial No. 736,768.

To all whom it may concern:

Be it known that I, GEORGE B. OWEN, a citizen of the United States, residing at Winsted, Litchfield county, State of Connecticut, have invented certain new and useful Improvements in Gear-Wheels, of which the following is a full, clear, and exact description.

The present invention relates to toothed gearing and is especially designed to provide a gearing of this type which will obviate "back lash" and will take up the space between its teeth and those of an intermeshing gear. Such a construction is desirable generally and of general use, and is especially desirable and has proven effective in practice when used in connection with clocks and other regulators, as it prevents the dropping of the hands of the clock and insures the steady revolution thereof or of a dial or other moving part of a regulator. To this end, I provide a gear comprising a plurality of complementary toothed sections mounted in axial alignment and for relative movement, these sections being arranged with their corresponding teeth overlapping, and resilient connecting means being provided between adjacent sections. Such a structure is effective in taking up the space between teeth when intermeshed with those of a coöperating gear. These and other advantages will be apparent from the following detailed specification taken in connection with the accompanying drawings forming part thereof and illustrating a preferable embodiment of my invention as applied to the gear train of a clock mechanism.

In these drawings, Figure 1 is a fragmentary view in front elevation of a clock frame showing a gear train operating the hands of a clock, said train embodying a gear constructed in accordance with the present invention. Fig. 2 is a detail on an enlarged scale and in front and edge elevation, of my improved form of gear, detached. Fig. 3 is a view in front and edge elevation of one section of the gear, detached. Fig. 4 is a detail in front and edge elevation of the other and coöperating section, likewise detached. Fig. 5 is a detail of the gear spring. Fig. 6 is a fragmentary view on an enlarged scale of the teeth of the

sectional gear. Fig. 7 is a similar view showing such gear teeth intermeshing with those of another gear.

Referring to the drawings by numerals, 1 indicates the front plate of a clock frame, and 2 and 3 the minute and hour hands, respectively, of the clock.

4, 5, 6, 7 and 8 designate coöperating gear elements forming the gear train for the clock hands, the arrangement being purely conventional. The gear 4, in the present illustration, is connected with the minute hand, while the gear 5 is connected with the hour hand. In the case of clocks and other regulators, back lash on the part of the gearing noticeably interferes with the accurate indication by the regulator and my improved form of gear is of particular utility when used in such a connection. The gear 4 in the present instance, is constructed in accordance with my invention and comprises complementary circular toothed sections 9 and 10, the section 10 being provided with an annular recess 11 and with a central hub portion 12 reduced in diameter at its end as at 13. The coöperating section 9 is provided with an annular recess 14 corresponding to the recess 11 of the coöperating gear section, and with a central aperture 15 designed to fit over the reduced end 13 of the hub of the first section of the gear, so as to permit relative movement between the two gear sections. The section 9 is preferably mounted on the hub 13 of section 10, and therefore in axial alignment therewith, and with its inner recessed face 14 resting against the hub portion 12 of said section. A coiled spring 16 is seated within the coöperating recesses 14 and 11 of the two sections of the gear, the ends of the spring being bent transversely and being inserted in apertures 17 in each of the gear sections, this spring being tensioned to position the teeth of one gear section so as to overlap slightly the teeth of the adjacent and coöperating gear section, as indicated most clearly in Figs. 6 and 7 of the drawing. It will be obvious therefore, that when a gear constructed as described, intermeshes with another gear of the usual type, its teeth will engage between adjacent teeth of a coöperating gear, and will be held thereagainst under the tension of the coil spring which acts to take up the space be-

tween the teeth when engaged, thereby preventing back lash, and insuring the smooth and steady revolution of the parts controlled by said gearing.

5 I have shown and described my improved form of gear as applied and connected with a clock mechanism, but it is, of course, obvious that its use is not confined to this art alone, and also that the details of construction 10 may be modified within the spirit of the invention and the scope of the appended claims.

What I claim is:

15 1. A gear comprising a plurality of complementary toothed sections mounted in axial alinement and for relative movement and each having their adjacent faces provided with axially alined annular recesses forming a housing, a spring seated in said housing 20 interconnecting said sections and normally tending to exert a strain on said sections in opposite directions, said spring extending around the axis of said gear.

25 2. A gear comprising two complementary toothed sections mounted in axial alinement and for relative movement, one of said sections being provided with a hub, and each of said sections having their adjacent faces formed with annular recesses therein providing a housing, and a coiled spring seated 30 within said housing and interconnecting said sections and normally tending to exert a strain on said sections in opposite directions,

said spring extending around the axis of said gear.

35

3. As an article of manufacture, a gear for regulators comprising two complementary toothed sections, one of said sections being provided with a hub and the other of said sections being rotatably mounted thereon, the adjacent faces of each of said sections being formed with axially alined annular recesses forming a housing, and a coiled spring seated within said housing interconnecting said sections and normally tending to exert a strain on said sections in opposite directions, said spring extending around the axis of said gear.

40

45

4. In an article of manufacture, a gear comprising two complementary toothed sections connected together concentrically but capable of limited independent rotation, an annular recess in the face of one of said toothed sections, said recess facing the other toothed section and forming therewith a housing, a coiled spring arranged in said housing, the coil of said spring lying within the plane of said housing, and one end of said spring being anchored to one of said sections and the other end thereof being anchored to the other of said sections.
